(57) **CLAIM**

The ornamental design for a knob for gas induction oven range, as shown and described.

DESCRIPTION

1. Knob for gas induction oven range
 1.1 is a perspective view of a knob for gas induction oven range, showing our new design;
 1.2 is a front elevation view thereof;
 1.3 is a rear elevation view thereof;
 1.4 is a left-side elevation view thereof;
 1.5 is a right-side elevation view thereof;
 1.6 is a top plan view thereof;
 1.7 is a bottom plan view thereof;
 1.8 is another perspective view thereof, in a use condition; and
 1.9 is another perspective view thereof, in another use condition.

The broken lines in the drawing figures are included for the purpose of illustrating environment and form no part of the claimed design.

1 Claim, 9 Drawing Sheets
